UNITED STATES PATENT OFFICE.

WILLIAM BUTLER AND LYMAN H. ZEIGLER, OF REDKEY, INDIANA, ASSIGNORS TO THE MARIETTA GLASS COMPANY, OF SAME PLACE.

DESIGN FOR A PATTERN FOR SHEET-GLASS.

SPECIFICATION forming part of Design No. 26,311, dated November 17, 1896.

Application filed September 14, 1896. Serial No. 605,821. Term of patent 7 years.

To all whom it may concern:

Be it known that we, WILLIAM BUTLER and LYMAN H. ZEIGLER, of Redkey, in the county of Jay and State of Indiana, have invented a new and original Design for Sheet or Plate Glass, of which the following is a full, clear, and exact description, reference being had to the accompanying drawing, which shows in plan view a sheet of glass embodying my design.

The design consists in a sheet or plate of glass having thereon a pattern substantially as herein shown and described.

As shown in the drawing, the glass has im-

pressed thereon a pattern consisting of ray-shaped or star-shaped figures with interspersed fern-like tracery having curved lines.

We claim—

The design for sheet or plate glass substantially as herein shown and described. 20

In testimony whereof we have hereunto set our hands.

WILLIAM BUTLER.
LYMAN H. ZEIGLER.
